E. DEMBOWSKY.

ENGINE.

APPLICATION FILED JAN. 20, 1919.

1,312,838.

Patented Aug. 12, 1919.

Emil Dembrowsky
My Frederick V. Winters,
Attorney.

UNITED STATES PATENT OFFICE.

EMIL DEMBOWSKY, OF METUCHEN, NEW JERSEY.

ENGINE.

1,312,838.

Specification of Letters Patent.

Patented Aug. 12, 1919.

Application filed January 20, 1919. Serial No. 272,074.

To all whom it may concern:

Be it known that I, EMIL DEMBOWSKY, a citizen of the United States, residing at Metuchen, in the county of Middlesex and State of New Jersey, have invented certain new and useful Improvements in Engines, of which the following is a full, clear, and exact specification.

This invention relates to engines which 10 may also be used as pumps, and is an improvement over the device of a similar nature which is disclosed in Patent No. 1,041,606, issued to me on October 15, 1912.

It is the aim of the present invention to 15 simplify the construction of the patented device by eliminating one of the crank shafts, the connecting gears therefor, and the slides between the pistons. To this end a rigid connecting bar extends between the 20 two pistons and its movements are controlled so that said pistons will move synchronously, as in the patent, by the provision of rocking guides which are arranged in line with the inlet and outlet ports but 25 do not obstruct them. Other objects will appear as the description proceeds.

The invention will be first hereinafter described in connection with the accompanying drawings, which constitute part of this 30 specification, and then more specifically defined in the claims at the end of the description.

In the accompanying drawings, wherein similar reference characters are used to 35 designate corresponding parts throughout the several views:—

Figure 1 is a side elevation of an engine constructed substantially in accordance with this invention.

40 Fig. 2 is a section on the line II—II of Fig. 1 on a larger scale and showing one position of the pistons in solid lines and another position in dotted lines.

Fig. 3 is a section on the line III—III of 45 Fig. 2, and

Fig. 4 is a diagrammatic view showing the pipe connections to the inlet and outlet ports and the reversing valve.

The engine casing 1 is preferably supported 50 by brackets 2 from the side of a stand 3 which has a journal 4 at its upper end for the drive shaft 5, as shown in Fig. 1. A pulley 6 is mounted on one end of said shaft 5 while its other end is connected to the 55 crank 7 which rotatably engages one piston 8 in one cylinder 9 of the casing. Another

cylinder 10 similar to the cylinder 9 is provided in the casing, and both cylinders open at 11 and 12 into each other and to the inlet port 13 and outlet port 14 which communicate with the casing through opposite walls 60 of the casing between the openings 11 and 12 of the cylinders.

In the cylinder 10, which is equal in size to the cylinder 9, as in the patent above referred to, a rotary piston 15 is arranged, and said piston is connected by a rigid, preferably integral, connecting bar 16 to the piston 8 in the cylinder 9. It will be noted that there is no crank connected directly to 65 the piston 15, as in the patent, but guiding means is provided for insuring the synchronous movement of the two pistons so as to produce the same results as the patented device. 75

Said guiding means comprises side pieces 17 and 18 set in the sides of the casing across the inlet and outlet ports respectively and having ports or openings 19 and 20 registering with said inlet and outlet ports, as shown 80 in Fig. 3, and rocking guides 21 and 22 working between said side pieces 17 and 18, respectively, and the opposite sides of the connecting bar 16. Each of the side pieces 17 and 18 has lateral beads 23 and 24 which 85 overlap the edges of the openings 11 and 12 of the two cylinders, as shown in Fig. 2, and are adapted to engage and fit inwardly cut grooves 25 and 26 in the pistons at either side of the connecting bar 16 when said 90 pistons straddle the openings 11 and 12. This construction allows for the difference in the distances between the centers of the two pistons at different points in their synchronous rotation, and makes it possible to 95 employ the rigid connecting bar in place of the slides used in the patent previously mentioned.

The rocking guides 21 and 22 each has a recess 27 for placing the inlet and outlet 100 ports in communication with both cylinders, as illustrated in Fig. 3. One end of each of said rocking guides has ribs 28 at opposite sides of the recess 27 and fitting loosely in a groove 29 in the adjacent side piece 17 or 105 18, while the other end 30 of said rocking guide loosely fits in a groove in the middle portion of the connecting piece, as at 31, Fig. 2. The end of the rocking guide which carries the ribs 28 may be broader than the 110 end 30, and is curved, as at 32, to conform to the arc of movement of said guide as it

rocks back and forth in guiding the connecting bar and pistons from the position shown in solid lines in Fig. 2, in the direction of the arrows, to the dotted line position, then 5 to the position exactly the reverse of the solid line position, and finally to the position directly the reverse of the dotted line position, and so on throughout one revolution after another as long as the propelling 10 force acts in the direction indicated.

When the device is used as an engine, steam, or other motive fluid, is supplied through the inlet port 13 and operates upon the connecting bar and pistons as just described, the power being taken off at the 15 pulley 6. When the device is used as a pump, power is applied to the pulley and through it to the crank and pistons, whereby fluid introduced through the inlet port 13 20 is forced around in the cylinders and out through the outlet port 14.

As illustrated in Fig. 4, a four-way valve 33 may be placed in the pipes 34 and 35 leading respectively to the inlet and outlet 25 ports so as to place either one of said ports in communication with a supply pipe 36 and the other one in communication with a discharge pipe 37. The operation of the engine or pump may in this way readily be reversed 30 by means of the valve 33, as indicated in Fig. 4 by solid line arrows leading to the inlet port and dotted arrows leading to the outlet port.

Having thus described my invention, what 35 I claim as new and desire to secure by Letters Patent of the United States is:—

1. The combination with a pair of similar cylinders arranged side by side and having 40 openings in their adjacent sides communicating with one another, inlet and outlet ports communicating with said cylinder openings at opposite sides, rotary pistons in said cylinders, a rigid connecting bar between said pistons and constituting a partition between the 45 inlet and outlet ports, a crank operatively engaging the piston of one of the cylinders, and means externally of the connecting bar and the other cylinder for causing the piston in the latter to move synchronously 50 with the piston in the first cylinder.

2. The combination with a pair of similar cylinders arranged side by side and having 55 openings in their adjacent sides communicating with one another, inlet and outlet ports communicating with said cylinder openings at opposite sides, rotary pistons in said cylinders, a rigid connecting bar between said pistons and constituting a partition between the inlet and outlet ports, a 60 crank operatively engaging the piston in one cylinder, and rocking guides engaging the opposite faces of the connecting bar for causing the piston in the other cylinder to

move synchronously with the piston in the first cylinder.

3. The combination with a pair of similar cylinders arranged side by side and having 65 openings in their adjacent sides communicating with one another, inlet and outlet ports communicating with said cylinder openings 70 at opposite sides, rotary pistons in said cylinders, a rigid connecting bar between said pistons and constituting a partition between the inlet and outlet ports, a crank operatively engaging the piston in one cylinder, 75 and rocking guides engaging the opposite faces of the connecting bar for causing the piston in the other cylinder to move synchronously with the piston in the first cylinder, 80 said rocking guides being arranged in line with the inlet and outlet ports, respectively, and having recesses therein bridging said ports.

4. The combination with a pair of similar cylinders arranged side by side and having 85 openings in their adjacent sides communicating with one another, inlet and outlet ports opening into said cylinder openings at opposite sides, rotary pistons in said cylinders, a rigid connecting bar between said pistons 90 and constituting a partition between the inlet and outlet ports, a crank operatively engaging the piston of one of the cylinders, and rocking guides engaging the opposite faces of the connecting bar for causing the piston 95 in the other cylinder to move synchronously with the piston in the first cylinder, means for retaining the outer ends of said guides against traveling other than by a rocking movement, and means for preventing the 100 inner ends of said guides from moving along the connecting bar.

5. The combination with a pair of similar cylinders arranged side by side and having 105 openings in their adjacent sides communicating with one another, inlet and outlet ports communicating with said cylinder openings at opposite sides, rotary pistons in said cylinders, a rigid connecting bar between said pistons and constituting a partition between the inlet and outlet ports, a crank operatively engaging the piston of one cylinder, rocking guides engaging the 110 opposite faces of the connecting bar for causing the piston in the other cylinder to move synchronously with the piston in the first cylinder, beads along the edges of the openings in the cylinders projecting slightly into said cylinders, and clearance grooves in the pistons adjacent the junctures of the connecting bar therewith to coöperate with said beads for the purpose specified.

In testimony whereof I have signed my name to this specification.

EMIL DEMBOWSKY.
